UNITED STATES PATENT OFFICE.

ENGLAND J. BARKER, OF CHICAGO, ILLINOIS.

TYPE-WRITER ATTACHMENT.

1,172,758.

Specification of Letters Patent. Patented Feb. 22, 1916.

Application filed December 19, 1914. Serial No. 878,015.

To all whom it may concern:

Be it known that I, ENGLAND J. BARKER, a citizen of the United States, residing at Chicago, in the county of Cook and State of Illinois, have invented new and useful Improvements in Type-Writer Attachments, of which the following is a full, clear, and exact description.

My invention relates to attachments for supplying paper from a continuous roll of paper to the platen of a typewriting machine.

One of the objects of my invention is to supply the paper from several continuous rolls in such manner that it will not twist or buckle, but will always feed to the platen at right angles to the axis thereof.

Another object is to supply this paper from rolls journaled below the top of the table which supports the typewriting machine, out of the way of the typist, and so as to protect the hanging slack of the paper from being soiled. Yet another object is to improve the means for guiding the paper after it leaves the platen. And yet another object is to separate the paper just before it is fed to the platen of the typewriter to enable the operator to grasp and adjust the web of each sheet of paper so as to make the printed matter on each sheet register with the printed matter on the others.

These and other important objects relating to the simplification of the construction of said attachment I accomplish by the means hereinafter fully described, and as particularly pointed out in the claims.

In the drawings: Figure 1 is a side elevation of a table and a typewriting machine embodying my invention, showing a part of the structure below the top of the table broken away. Fig. 2 is a plan view of my invention showing it applied to the broken away rear parts of said machine and said table. Fig. 3 is a rear view of the paper feeding rollers, a fragment of the top of the table, the uppermost paper roll and the broken away upper portion of the depending supporting frame-work of my invention, drawn to a larger scale. Fig. 4 is a vertical section taken on dotted line 4-4, Fig. 2, drawn to a larger scale. Figs. 5 and 6 are detail views showing, respectively, a

side elevation and a transverse vertical section of the standard in which the feed-rollers are journaled. Fig. 7 is a longitudinal section of one end of the roller upon which the roll of paper is mounted. Figs. 8, 9, 10 and 11 are detail views showing, respectively, the front, the rear and a transverse section of the paper shield for the platen, and an edge view of a dog used in connection therewith.

Referring to the drawings, A represents the top of a table, which is supported by legs *a* and has, preferably, just in front of the transverse vertical plane of the rear legs, a comparatively long transversely elongated opening B, and just to the rear of opening B and said rear edge a shorter transversely elongated opening *b*. A typewriting machine C is mounted on the top of said table in front of and so that its platen will be parallel with the direction of length of said opening B, which latter corresponds to and is coterminal with the extent of the reciprocable throw of said platen.

Depending down from the top of the table immediately to the rear of the rear legs *a* thereof and down from the underside of said top between the two openings B, *b*, thereof, are hanging frames *c*, *c*. These frames *c* consist, preferably of angle irons that extend nearly to the floor, and are provided with corresponding equi-distant rearwardly extending brackets *d*, which, near their rear ends, have bearings for the rollers on which the rolls of paper which it is desired to feed to the platen of the typewriting machine are mounted. These rollers comprise a hollow metal cylinder D, the ends of which are closed by the depressed central portion of a metal head E, the diameter of which latter is such that the marginal portions form end-flanges for the cylinder D. These heads E are provided with axially extending journals consisting of a spindle *e*, the inner end of which is headed to prevent its withdrawal, and the outer portion of which next said head is surrounded by a sleeve *e'*. When the spindles of these rollers D are mounted in bearings in the rear ends of brackets *d* of the hanging frame *c*, another sleeve F, whose outer end is flanged, is pushed over the outer end of

spindle *e* until it bears against the under surface of the arm *d*, and thus confines the journals of said rollers in their bearings.

Secured to and arising from the top of the table back of opening *B*; at a point slightly to the side of the ends of openings *b*, are standards *G*, *G*. An upper and a lower feed roller 2 and 3 are adjustably secured upon horizontal shafts 4 and 5 that have bearings 5 in standards *G*, *G*. The bearings for the upper shaft 4 are stationary, whereas the bearings for the lower shaft 5 are in journal-blocks 6 that are vertically movable in vertically elongated chambers in the lower portion 10 of standards *G*, and are kept at the limit of their upward movement by coil-springs 7 that are retained in position and adjusted by screws 8 tapped up through the bottom of said standards. The diameters of 15 the portion of shaft 5 within the journal-blocks 6 are, preferably, reduced in diameter, and the openings in standards *G* through which these reduced portions of the shaft extends are elongated vertically to permit 20 of a limited vertical movement of said shaft and the feed roller 3 mounted thereon.

The continuous strips of paper from the rolls on rollers *D* extend up through openings *b* in the top of the table, then between feed-rollers 2 and 3 and then down through opening *B*. In order to separate said feed-rollers to facilitate the insertion and passage of said paper between the same, particularly when the paper is first threaded through the 30 machine preparatory to utilizing my improved attachment, it is desirable to separate the lower from the upper feed-roller. This I do by means of somewhat crescent shaped cams 9 the lower outer edges of 35 which engage the portion of shaft 5 next standards *G*. These cams are fulcrumed to the inner surface of standards *G* mediate their ends and their upper branches are curved rearwardly and are adapted to be engaged by fingers 10 secured to and projecting forward from a rock-shaft 11, which latter is journaled in standards *G* at points in the rear of shafts 4 and 5, and in a horizontal plane between them. One end of said 40 rock-shaft extends through its bearings and is provided with a knob or mill-disk with which to turn the same. When shaft 11 is turned so that the fingers 10 bear down on the upper extension of cams 9, the lower branches of said cams bear upon shaft 5 and 45 push it and the feed-roller 3 downward away from roller 2 so that the paper can be easily threaded between the same. I prefer to make feed-roller 3 longer than feed-roller 2 and to mill the central portion of 50 both of said rollers.

The paper strips that pass down through opening *B* extend nearly to the bottom of a basket made of wire or other suitable material. The upper edges of this basket are

secured in any suitable manner to the underside of the top of the table, and the basket extends down nearly to the floor, and the hanging slack paper that enters it is protected from injury and from being soiled. 70 The paper then extends up out of said opening *B* again to and over a series of guide-rollers 13. These guide-rollers are horizontal and are journaled at equal distances apart in the upwardly extending rearwardly 75 inclined brackets 14 that separate the several strips of paper before they are fed to the platen of the typewriting machine. These paper strips, thus separated, extend horizontally forward from rollers 13 over a 80 vertically arranged series of guide-rollers 15 that are journaled in uprights 16, which latter are connected by a suitable horizontal plate 17, and together therewith form the end-frames of a longitudinally reciprocable 85 guide-truck for the paper, which is adapted to travel from side to side on a horizontal shaft 18, simultaneously with the carriage of the typewriter in which the platen is journaled. Shaft 18 is journaled in bearings in 90 the upper ends of vertical posts 19 the base-plates of which are secured to the top of the table at points intersected by the transverse vertical plane in the rear of the frame of the typewriting machine, and at suitable distances on either side of the same beyond the ends of elongated opening *B*. This shaft 18 is in a horizontal plane slightly above the axis of the platen, and the end-frames of the traveling truck, just referred to, have shoes 95 20 secured thereto, the undersides of which are provided with grooves into which shaft 18 enters.

Shaft 18 derives its motion from the platen, one of the journals 21 of which latter extends beyond its bearings in the transversely reciprocable carriage (not shown) of the typewriting machine and has a sprocket 22 on its end that is connected to a similar sprocket 23 on shaft 18 by means of 105 a chain 24. Shaft 18 is provided with a suitable longitudinal groove 25, and sprocket 23 is provided with a suitable bolt 24 that is tapped through its boss into said groove 25 to permit said sprocket to move longitudinally on shaft 18 simultaneously with the carriage of the typewriting machine, but to move on the axis thereof or rotate therewith. The end of shaft 18, opposite that nearest which sprocket 23 is mounted, extends 110 through its bearing and is provided with a sprocket 26 which, through the medium of a chain 27, imparts motion to a sprocket 28 on the end of the feed roller shaft 4 and rotates the upper feed roller in such direction 115 as to draw the record strips from the paper supply rollers at such speed as to always maintain the slack hanging portion of the paper between feed rollers 2 and 3 and the guide rollers 13. 120

From the guide rollers 15 the paper strips extend down under the platen 30, and after said strips leave the platen the paper passes up over a shield 29. This shield is provided 5 at its ends with rearwardly extending lugs 31 in which the ends of a transverse rock-shaft 32 are journaled. The shield is bent rearwardly over the platen, and in order to keep the paper against the same I employ 10 a comparatively narrow plate 33 the ends of which are provided with upwardly projecting wings which are placed in front of said shaft 32. Just beyond the end of the shield 29, preferably, next lugs 31, shaft 32 15 is provided with dogs 36 that project upward and forward and have their upper ends hooked and normally engaging the upper edges of the fingers 35, which latter project longitudinally from the wings of the 20 plate 33. The incisions made in the ends of the dogs to form the hooks are such that when the dogs engage said fingers 35 they not only hold plate 33 down but space it apart from the shield such a distance that 25 the paper from the platen can pass between the same. Shaft 32 is provided with a coil torsion spring 37 about midway its length one end of which latter is secured in said shaft and the other end bears against the 30 back of the shield, as shown.

In order to prevent the sagged or slack portion of the paper below the top, from being soiled by the operator's feet or in any other manner, I have provided a basket 40, 35 the frame of which is, preferably, made of metal strips 41 and the sides of which are, preferably, made of woven wire. The open top of this basket is secured under the top of the table immediately in front of the 40 pendent frame in which the supply rollers are journaled in such position that the paper from the feed-rollers will sag down into it, and then pass upward through opening B to the guide-rollers 13. This basket may 45 be dispensed with, but I much prefer its use.

What I claim as new is:

1. The combination with a writing machine of the kind specified having a reciprocable carriage and a rotatable platen 50 journaled therein, of a support for said machine consisting of a flat top a portion of which back of the same is cut away, a suitable frame depending from said top, a supply-roller journaled in said frame upon 55 which a continuous sheet of paper is mounted, feed-rollers to which said paper from said supply-roller is fed and from which the paper sags down below said top, and means above said top which is supported independently of said carriage, but is reciprocable therewith up over which the sagged stretch of paper passes to the platen.

2. The combination with a writing machine of the kind specified having a reciprocable carriage and a rotatable platen jour-

naled therein, of a support for said machine consisting of a flat top having two elongated openings therein parallel to the line of motion of said carriage, a suitable frame depending from said top, a roller journaled 70 therein parallel to one of said openings upon which a roll of paper is journaled, feed-rollers supported above said top whose axes are parallel to that of said feed-roller and from which the paper sags down through 75 the other of said openings, a suitable track independent of the typewriting machine, and means above said support and supported independently of said carriage but reciprocable on said track up over which said 80 sagged stretch of paper passes to the platen.

3. The combination with a writing machine comprising a reciprocable carriage and a rotatable platen journaled therein, of a supply-roller upon which is mounted a continuous roll of paper having stationary 85 bearings, a guide-roller for directing the paper to the platen which is supported independent of and is reciprocable longitudinally with said carriage, and means for 90 maintaining a hanging slack portion of said paper before it reaches said guide-roller.

4. The combination with a writing machine comprising a reciprocable carriage and a rotatable platen journaled therein, of a 95 plurality of supply-rollers upon which are mounted continuous rolls of paper having stationary bearings, guide-rollers for directing the paper to the platen which are supported independent of and are reciprocable 100 longitudinally with said carriage, and means for maintaining a hanging slack portion of said paper before it reaches said guide-rollers.

5. The combination with a writing machine comprising a reciprocable carriage, and a rotatable platen journaled therein, of a support having two parallel openings in the top thereof at the rear of said machine, a plurality of supply-rollers upon 110 which rolls of paper are mounted below said top arranged one below the other, two feed-rollers journaled one above the other above the top of said support between said slots; said paper being drawn by said feed-rollers up through one of said slots and discharged therefrom down through the other of said slots to provide a pendent slack portion between the same and said writing machine.

6. The combination with a writing machine comprising a reciprocable carriage and a rotatable platen journaled therein, of a support having openings in the top thereof at the rear of said machine, a plurality 115 of supply-rollers upon which rolls of paper are mounted below said top parallel to each other, two separable feed-rollers journaled one above the other above the top of said support between said slots; said paper be- 120 125 130

ing drawn by said feed-rollers up through one of said openings and discharged therefrom down through the other of said openings to provide a pendent slack portion between the same and said writing machine.

7. The combination with a writing machine comprising a reciprocable carriage and a rotatable platen journaled therein, of a support having two parallel openings in the top thereof at the rear of said machine, a plurality of supply-rollers upon which rolls of paper are mounted below said top parallel to said platen, two feed-rollers journaled one above the other above the top of said support between said slots vertically movable automatically, returnable bearings for one of said feed-rollers, cams for moving the last mentioned feed-roller away from its fellow, said paper being drawn by said feed-rollers up through one slot and discharged thereby down into the other slot to form a pendent slack portion between said feed rollers and the writing machine.

8. The combination with a writing machine comprising a reciprocable carriage and a rotatable platen journaled therein, of a support having two parallel openings in the top thereof at the rear of said machine, a plurality of supply-rollers upon which rolls of paper are mounted below said top arranged one below the other parallel to said platen, two feed-rollers journaled one above the other above the top of said support between said slots, vertically movable automatically returnable bearings for one of said feed-rollers, cams for moving the last-mentioned feed-roller away from its fellow, means driven by said platen for rotating the feed-roller that has stationary bearings, said paper being drawn by said feed-rollers up through one slot and discharged thereby down into the other slot to form a pendent slack portion between said feed rollers and the writing machine.

9. The combination with a writing machine comprising a reciprocable carriage and a rotatable platen journaled therein, of a support having two parallel openings in the top thereof at the rear of said machine, a plurality of supply-rollers upon which rolls of paper are mounted below said top arranged one below the other parallel to said platen, two feed-rollers journaled one above the other above the top of said support between said slots, guide-rollers journaled to the rear of but independently from said platen adjacent to the rear of the typewriting machine, said paper being drawn by said feed-rollers up through one of said slots and discharged therefrom down through the other of said slots to provide a pendent slack portion between the same and said guide-rollers.

10. The combination with a writing machine comprising a reciprocable carriage and

a rotatable platen journaled therein, of a support having two parallel openings in the top thereof at the rear of said machine, a plurality of supply-rollers upon which rolls of paper are mounted below said top arranged one below the other parallel to said platen, two separable feed-rollers journaled one above the other above the top of said support between said slots, guide-rollers journaled to the rear of but independently from said platen adjacent to the rear of the typewriting machine, said paper being drawn by said feed-rollers up through one of said slots and discharged therefrom down through the other of said slots to provide a pendent slack portion between the same and said guide-rollers.

11. The combination with a writing machine comprising a reciprocable carriage and a rotatable platen journaled therein, of a support having two parallel openings in the top thereof at the rear of said machine, a plurality of supply-rollers upon which rolls of paper are mounted below said top arranged one below the other parallel to said platen, two feed-rollers journaled one above the other above the top of said support between said slots, guide-rollers journaled independently to the rear of but reciprocable simultaneously with said platen adjacent to the rear of the writing machine, vertically movable automatically returnable bearings for one of said feed-rollers, cams for moving the last-mentioned feed-roller away from its fellow, said paper being drawn by said feed-rollers up through one slot and discharged down into the other slot to form a pendent slack portion between said feed rollers and the guide-rollers.

12. The combination with a writing machine comprising a reciprocable carriage and a rotatable platen journaled therein, of a support having two parallel openings in the top thereof at the rear of said machine, a plurality of supply-rollers upon which rolls of paper are mounted below said top arranged one below the other parallel to said platen, two feed-rollers journaled one above the other above the top of said support between said slots, guide-rollers journaled independently to the rear of but reciprocable simultaneously with said platen adjacent to the rear of the writing machine, vertically movable automatically returnable bearings for one of said feed-rollers, cams for moving the last-mentioned feed-roller away from its fellow, means driven by said platen for rotating the feed-roller that has stationary bearings, said paper being drawn by said feed-rollers up through one slot and discharged down into the other slot to form a pendent slack portion between said feed rollers and the guide-rollers.

13. The combination with a writing machine having a reciprocable carriage and a

5 rotatable platen journaled therein, a plurality of paper supply-rollers journaled in stationary bearings at the rear of and independent of said machine, and guide-rollers reciprocable simultaneously with said carriage, but supported independently thereof and to the rear of the same.

14. The combination with a writing machine having a reciprocable carriage and a 10 rotatable platen journaled therein, a plurality of paper supply-rollers in stationary bearings at the rear of and independent of said machine, guide-rollers, a supporting frame therefor reciprocable simultaneously 15 with said carriage, a rotatable horizontal shaft having stationary bearings back of said machine upon which said supporting frame is mounted and which derives motion from said platen, and feed-rollers interposed 20 between said supply-rollers and guide-rollers that derive motion from said horizontal shaft.

15. The combination with a writing machine having a reciprocable carriage and a 25 rotatable platen journaled therein, a plurality of paper supply-rollers in stationary bearings at the rear of and independent of said machine, a guide-roller, a supporting frame therefor reciprocable simultaneously 30 with said carriage, a rotatable horizontal shaft having stationary bearings back of said machine upon which said supporting frame is mounted and which derives motion from said platen, feed-rollers interposed be- 35 tween said supply-rollers that derive motion from said horizontal shaft, and means for maintaining a pendent slack portion of the paper between said feed-rollers and guide-rollers.

40 16. The combination with a writing machine having a reciprocable carriage and a rotatable platen journaled therein, a support for said machine having two transversely elongated slots back of the same, a 45 plurality of paper supply-rollers in stationary bearings below said top at the rear of and independent of said machine, guide-rollers, a supporting frame therefor reciprocable simultaneously with said carriage, a rotatable horizontal shaft having 50 stationary bearings back of said machine upon which said supporting-frame is mounted and which derives motion from said platen, feed-rollers, bearings therefor 55 interposed between said slots, and means for rotating said feed-rollers that derive motion from said horizontal shaft.

17. The combination with a writing machine having a reciprocable carriage and a 60 rotatable platen journaled therein, a support for said machine having two transversely elongated slots back of the same, a plurality of paper supply-rollers in stationary bearings below said top at the rear of 65 and independent of said machine, guide-roll-

ers, a supporting-frame therefor reciprocable simultaneously with said carriage, a rotatable horizontal shaft having stationary bearings back of said machine upon which said supporting-frame is mounted and 70 which derives motion from said platen, feed-rollers, bearings therefor interposed between said slots, means for rotating said feed-rollers that derive motion from said horizontal shaft, and means for maintaining 75 a pendent slack portion of the paper between said feed-rollers and guide-rollers.

18. The combination with a writing machine of the kind specified having a reciprocable carriage and a rotatable platen journaled therein, of a support for said machine consisting of a flat top a portion of which back of the same is cut away, a suitable frame depending from said top, a supply-roller journaled in said frame upon which 80 a continuous sheet of paper is mounted, feed-rollers whose axes are parallel to said supply-roller to which said paper from said supply-roller is fed and from which the paper sags down below said top, and means 85 above said top which is supported independent of said carriage but is reciprocable therewith up over which the sagged stretch of paper passes to the platen.

19. The combination with a writing machine of the kind specified having a reciprocable carriage and a rotatable platen journaled therein, of a support for said machine consisting of a flat top having two elongated openings therein parallel to the line of 90 motion of said carriage, a suitable frame depending from said top, a supply roller top whose axes are parallel to that of said openings upon which a roll of paper is 95 journaled, feed-rollers supported above said top whose axes are parallel to that of said supply-roller and from which the paper sags down through the other of said openings, and means above said support and supported independent of said carriage but reciprocable therewith up over which said 100 sagged stretch of paper passes to the platen. 105

20. The combination with a writing machine of the kind specified having a reciprocable carriage and a rotatable platen journaled therein, of a support for said machine consisting of a flat top a portion of which back of the same is cut away, a suitable frame depending from said top, a supply-roller journaled in said frame upon which 110 a continuous sheet of paper is mounted, feed-rollers to which said paper from said supply-roller is fed and from which the paper sags down below said top, and a basket secured to said support below the said top into which the sagged portion of the paper enters. 115

21. The combination with a writing machine of the kind specified having a reciprocable carriage and a rotatable platen jour-

naled therein, of a support for said machine consisting of a flat top a portion of which back of the same is cut away, a suitable frame depending from said top, a supply-
5 roller journaled in said frame upon which a continuous sheet of paper is mounted, feed-rollers to which said paper from said supply-roller is fed and from which the paper sags down below said top, means
10 above said top which is supported independently of said carriage but is recipro-

cable therewith up over which the sagged stretch of paper passes to the platen, and a basket secured to said support below the said top into which the sagged portion of 15 the paper enters.

In witness whereof, I have hereunto set my hand this 12th day of December, 1914.

ENGLAND J. BARKER.
